BAKERY TRUCK PULL TOY

Helen H. Malsed, 3621 45th Ave. W., Seattle, Wash.

Filed Jan. 15, 1963, Ser. No. 73,183

Term of patent 14 years

(Cl. D34—15)

FIG. 1

FIG. 2

FIG. 3

I claim:

The ornamental design for a bakery truck pull toy, substantially as shown.
